UNITED STATES PATENT OFFICE.

JAMES L. ADAMS, JR., OF WILKINSBURG, PENNSYLVANIA, ASSIGNOR TO WESTINGHOUSE ELECTRIC AND MANUFACTURING COMPANY, A CORPORATION OF PENNSYLVANIA.

CIRCUIT-BREAKER.

1,175,330.

Specification of Letters Patent. Patented Mar. 14, 1916.

Application filed December 5, 1910. Serial No. 595,667.

To all whom it may concern:

Be it known that I, JAMES L. ADAMS, Jr., a citizen of the United States, and a resident of Wilkinsburg, in the county of Allegheny and State of Pennsylvania, have invented a new and useful Improvement in Circuit-Breakers, of which the following is a specification.

My invention relates to automatic electrically operated circuit breakers of the railway type and it has special reference to such devices as are adapted to tie together the adjacent segregated sections of trolley wires or third-rails of an electric railway system.

The object of my invention is to provide a device of the above-indicated class that shall be simple, rugged and compact in construction, effective and reliable in operation and adapted to automatically open under predetermined abnormal circuit conditions on either of the adjacent sections which it ties together, and further adapted to automatically reconnect said sections only when substantially normal conditions are restored to both sections.

In electric railway systems, it is particularly desirable to sectionalize the entire system in order that trouble on any one section may be localized, and not interrupt the traffic of the whole system. Furthermore, it is of prime importance to maintain good voltage regulation, to reduce the line losses to a minimum and to decrease the initial expenditure for copper, and it has been customary, therefore, to tie together the various sections under normal operating conditions in order that the copper may be employed most efficiently.

If knife switches or non-automatic circuit-closing devices are used at the section breaks, serious grounds or short circuits on any section are apt to disable the entire interconnected system, until the damaged section has been cut out by hand or the source of trouble removed. If fused switches are used, they will promptly disconnect the defective section, but, when a fuse has been blown, it must be replaced by hand, which may involve more or less repeated delays and consequent lowering of the average distributed potential during such periods. It is, therefore, essential that any automatic tie-in device should be designed to open

promptly upon the occurrence of predetermined abnormal circuit conditions, and to automatically reconnect the segregated sections as soon as, and not until, practically normal conditions have been restored.

Heretofore, the results above mentioned have been accomplished; but only through the use of a more or less complicated system of wiring and a considerable number of relays and auxiliary switches which have proved unsatisfactory and objectionable from an operative standpoint on account of the cost of installation and maintenance and their unreliability under exposed service conditions.

According to my invention, I provide a self-contained electrically-operated circuit breaker which is adapted to automatically tie together two adjacent sections in the manner referred to, when, and only when, the voltage on each section is substantially normal, and to disconnect said sections under conditions of severe short circuit, serious grounds, or predetermined low voltage on either of the adjacent sections. If the several sections of a railway system be thus tied together, it will be seen that upon the occurrence of a predetermined abnormal circuit condition on any section, that particular section will be segregated from the rest of the system and remain segregated until normal conditions have again been restored.

In the accompanying drawings, Figure 1 is a view, in front elevation, of a circuit-breaker constructed in accordance with my invention. Fig. 2 is a view, partially in horizontal section and partially in plan, of the circuit breaker shown in Fig. 1, the sectional plane being taken intermediate the magnet coils shown in Fig. 1. Fig. 3 is a view, partially in vertical section and partially in side elevation, of a portion of the circuit-breaker shown in Fig. 1, and Fig. 4 is a diagrammatic view showing the circuit connections of the said circuit-breaker.

Referring to the drawings in detail, a circuit breaker 1 comprises a base or panel 2, a stationary magnet core structure 3, a movable core member 4, a plurality of magnet windings 5 and 6, a plurality of stationary contact terminals 7, a bridging contact member 8, a magnetic blow-out device

9 and an automatic release mechanism 10. If preferred, the base 2 and stationary magnet structure 3 may form part of, and be integral with, a cast iron or pressed steel 5 inclosing case.

The stationary core structure 3 is suitably mounted upon the base or panel 2 and comprises upper and lower yoke members 11 and 12, and side return magnetic circuit 10 members 13 and 14, which are secured between said yoke members. Parts 11 to 14, inclusive, may, if preferred, be formed in one piece. A salient pole member 16 is closely associated with the upper yoke member 11 and extends downwardly to a point approximately midway between the two yoke members.

A tube or sleeve 17 of non-magnetic material, which surrounds the salient pole member 16, extends from the upper yoke member 11 through the lower yoke member 12. The lower portion of the tube 17 is adapted to receive the movable core member or plunger 4, which is loosely fitted therein. 25 The upper surface of the plunger 4 is beveled off slightly, as shown in Fig. 3, to locally increase the magnetic density and thereby the drop of magnetic potential in the immediate vicinity of the plane of contact between said plunger and salient pole 16.

An insulating coupling 18 connects a projecting portion 19 of the movable core member 4 to a supporting member 20 from which the movable contact member 8 is pivotally 30 suspended to coöperate with the stationary contact terminals 7 when the circuit interrupter is closed.

The magnetic blow-out device 9 (through which the current is shunted when the main 40 contacts 7 and 8 are opened) is of well-known construction, and its function and mode of operation are old and familiar in the art. Therefore, no description of the same is considered necessary, and it is evident that any other suitable device for accomplishing the same purpose may be employed. If desired, in certain cases, such an auxiliary arc breaking device may be omitted entirely. Furthermore, the stationary contact terminals 7 and the coöperating bridging contact member 8 form no part of my invention, except as they perform functions essential to an operative combination, and they may also be replaced 50 by any other suitable devices.

The release mechanism 10 comprises a main lever member 25 which is pivotally mounted, near its lower end, upon a pin 26 which extends between bracket members 27. 60 Below the pivotal support of the main lever 25, is an extended portion 28, which carries a screw 29 for the purpose of adjusting the circuit-breaker to close at a predetermined voltage. A lever 30 is also pivotally supported, at one end, upon the shaft 26 and its

other end is located between the lower portion of the movable core member 4 and the insulating coupling 18 in such manner that its movement is dependent upon the movement of the core member 4, as will be readily understood. Furthermore, the lever 30 is adapted to engage the adjusting screw 29 when the core member 4 is in its lower position or when the main lever 25 is in the open position (shown dotted).

A threaded stud 31 is suitably secured to the operating lever 25 and is provided with a weight 32 and a nut 33 by means of which the operation of the release mechanism may be adjusted as desired. It is evident that the weight 32 may be replaced by any other equivalent device.

Secured to the upper end of the operating lever 25, is a cross arm 34 of conducting material which is preferably insulated from the lever 25 and carries auxiliary contact terminals 35 at its respective ends. As shown, the contact terminals 35 are of the carbon butt-contact type and are spring supported. However, terminals of any other suitable construction may be employed, and it is evident that the release mechanism may be so modified as to require but one auxiliary contact member instead of two. A bar of magnetic material 37 is mounted upon the cross arm 34, by means of screws 38, and constitutes a movable armature for a peculiar type of magnet structure to be hereinafter described. In order to prevent the armature 37 from "freezing" to the aforesaid magnet structure, suitable stops 36 are provided which may conveniently comprise the extended ends of the screws 38.

The stationary contact terminals 39 are suitably secured to the ends of conducting members 40 which are rigidly fastened to the panel or base 2, and said stationary contact terminals are so disposed as to coöperate with the movable contact terminals 35.

Between the upper and lower magnet coils 5 and 6, are disposed pole shoes 42 and 43 of magnetic material, which surround the sleeve or tube 17 and have projecting portions 44 and 45, respectively. The pole shoes 42 and 43 are of similar structure and are oppositely assembled, so that the extremities 46 of the said projecting portions form suitable engaging surfaces, which are aligned in substantially the same vertical plane and are arranged to coöperate with the movable magnetizable bar or armature 37. It is evident that any one of several more or less similar structures might be substituted for the above-described pole shoe and armature structure. Furthermore, a heavy ring 47 of non-magnetic but highly conducting material and of relatively large diameter surrounds the tube 17 between the magnetizable pole shoes 42 and 43.

In order to secure the shoes 42 and 43

rigidly together and maintain the engaging surfaces 46 in proper alignment to coöperate with the movable armature 37, a bar of non-magnetic material 50 is suitably fastened to the projecting portions 44 and 45 of said shoes. The ring 47 may, of course, be modified and adapted to serve this purpose, if desired.

The magnet coils 5 and 6 are alike, and are wound, assembled and connected to the system in such manner that they normally assist each other in acting upon the movable core member 4. One lead of the coil 6 is connected to a section 51 of trolley wire 15 or third-rail by means of a conductor 52, while one lead of the coil 5 is connected to an adjacent section 53 by a conductor 54. The two remaining leads from the coils 5 and 6 are connected together and grounded 20 through the coöperating stationary and movable auxiliary contact members 39 and 35, the conducting cross arm 34 and the conductor 57.

Inasmuch as the lever 30 is caused to engage the adjusting screw 29 when the movable core 4 is in its lower position, it is evident that variations in the length of the initial air-gap between the coöperating stationary and movable core members 16 and 4, respectively, may be secured by suitably 25 adjusting the screw 29. Hence, with full potential applied to both coils, the circuit-breaker may be adjusted so that it will just close the main contacts 7 and 8 under predetermined voltage conditions which are dependent upon the length of this air-gap, in accordance with well-known principles. Furthermore, if full closing potential be applied to one coil but a much lower voltage, 30 or none at all, be applied to the other coil, the plunger will not rise to close the main contacts.

Assuming that a normal voltage of 550 volts exists upon the two adjacent and non-interconnected sections 51 and 53 and that this potential is applied to both of the coils 5 and 6, the plunger 4 will be raised and the main circuit will be closed through coöperating contact members 7 and 8. While the 35 plunger 4 was in its lowest or open position, the under-voltage release lever 25 was forced by the weight of the plunger 4 and other movable parts of the circuit-breaker, to assume an upright position, with the auxiliary contact members 35 and 39 closed, and with armatures 37 adjacent to the pole shoes 46. As the plunger 4 rises, the under-voltage release lever 25 is retained in its upright or closed position by the attraction exerted 40 upon the armature 37 by the pole shoes 42 and 43, on account of the shunting of a certain portion of the main magnetic flux away from the air-gap above plunger 4 and through the pole shoe 42, armature 37 and pole shoe 43 by which the main air-gap 45

is more or less bridged. It is evident that, as the plunger 4 rises and thereby reduces the length of the main air-gap, there will be continually less tendency for the magnetic flux to take up the side or shunt path 70 through the armature 37, so that, after the plunger 4 strikes the salient pole member 16, the flux passing through armature 37 soon reaches a certain minimum value which is determined by the relative final reluctances 75 of the main and shunt paths.

The above-mentioned reluctances are both capable of such initial adjustment, as may be found necessary upon trial, by varying the length of non-magnetic stops 36, or by 80 very slightly beveling off the adjoining ends of the coöperating stationary and movable core members 16 and 4, thus introducing a very small air-gap over a greater or less percentage of the opposed face areas. It is usually of some advantage to have actual magnetic contact over at least a moderate percentage of the total opposed areas of the core members 16 and 4, so that the movable contact member 8 will be held solidly in contact with the terminals 7, even when the voltage impressed upon coils 5 and 6 shall have fallen to or beyond the minimum point at which the under-voltage release mechanism can be set to operate. 90

For all normal impressed voltages, the final magnetic pull exerted upon the armature 37, even after the plunger 4 and stationary core 16 have come into intimate contact, is sufficient to hold the contact members 100 35 in engagement with the coöperating contact members 39, in opposition to the pull of the weight 32.

In closing the breaker, just at the moment when the plunger 4 strikes the stationary core 16, the reluctance of the magnetic circuit, taken as a whole, and more particularly that portion of it in the immediate vicinity of this plane of contact, reaches a momentary minimum value which gradually 105 rises again to some extent as the main magnetic flux, with a more or less decided time lag, grows to its final maximum value. It is also evident that the magnetic potential, which is equal to the product of the values 110 of magnetic flux and the reluctance across the plane of contact of the stationary and movable core members 16 and 4, will also reach a similar and even more accentuated momentary minimum value, followed by a gradual rise to the final steady potential. But the amount of magnetism flowing through pole shoe 42, armature 37 and pole shoe 43 is determined by this magnetic potential and the pull upon armature 37 is proportional to the square of the flux 115 through it. Hence, if the highly conducting and non-magnetic ring 47 were not present, there would occur a very decided momentary falling off of the pull upon the ar- 120 130

mature 37, just as the breaker was closing, with a consequent tendency for the under-voltage mechanism to act just at this time and re-open the breaker. The breaker 5 would then again endeavor to close, the outcome being a repeated "pumping" or "hunting" action, which might go on indefinitely until the resulting arcing had ruined the main contact members. However, while the 10 breaker is closing and the magnetism is building up through the main air-gap between the staticary core 16 and the plunger 4, it must also necessarily increase through the ring 47, which being highly 15 conducting, tends to prevent such increase and, in doing so, obliges a greater than normal percentage of the total flux to temporarily take the side path around the ring and through the armature 37, thus compensating for, and practically annulling, the above-mentioned tendency to "hunt." By 20 suitably adjusting the position of the weight 32, it is evident that the coöperating stationary and movable contact members 35 and 39 may be caused to separate at any desired low voltage, thus interrupting the ground or return circuit connection of both 25 magnet coils 5 and 6 and causing the main contact members 7 and 8 of the interrupter 30 to be thereby automatically opened.

Past experience in electric railway work has demonstrated the inadvisability of setting such circuit breaking devices so that they will disconnect the adjacent sections 35 whenever a moderate fall of voltage occurs, for the reason that when such breakers open up and so segregate the several trolley or third-rail sections, there will usually result a further more or less general fall of operating voltage along all the trolley or third-rail conducting system, thus causing further interference with the general voltage supply. Such breakers are usually so adjusted 40 that they will not open up except under severe or extremely abnormal conditions. In electric railway systems employing voltages from 500 to 600 volts, it has been found desirable to set such interrupting devices so that they will open if the potential falls to 45 250 volts. In some cases, however, a 200 volt or even a 150 volt release setting may be preferred. Hence, the under-voltage release mechanism of the circuit breaker is so adjusted, by changing the position of the 50 weight 32, that when the voltage has fallen to the potential determined upon the shunted flux through the pole shoe 42, armature 37 and pole shoe 43 shall be just sufficient to hold up said armature and maintain the co- 55 operating contact terminals 35 and 39 in their closed positions.

If we assume that the voltage at the circuit breaker falls below the previously set limit, by reason of a serious ground or short 60 circuit somewhere upon the system, it is evi-

dent that the pull of the weight 32 upon the armature 37 will be in excess of the now reduced magnetic pull exerted upon said armature by the pole shoes 42 and 43, and, hence, the separation of the auxiliary contact members 35 and 39 is effected and the under-voltage release lever 25 assumes the position shown in dot and dash lines in Fig. 3.

Upon the separation of contact terminals 75 35 and 39, the ground or return connection of both magnet coils 5 and 6 is interrupted and whatever current may then flow through both coils in series will be in such direction as to neutralize the magnetic effect of both and allow the movable core member 4 to drop, thereby causing the bridging contact member 8 to separate from the stationary contact terminals 7 and segregate the feeders, the final break taking 80 place in the arc-disrupting device 9. In so doing, the lever 30, which is in engagement with the adjustable screw 29 when the release lever 25 is in its open position, is carried down and causes said release lever to be 85 raised to again effect the engagement of contact terminals 35 and 39, as will be readily understood. Thus, the ground connection for both magnet coils is at once re-established. Assuming that normal voltage 90 is again restored to both adjacent sections, the pull exerted upon the movable core member 4 causes said member to be raised, thereby effecting the closure of the coöperating stationary and movable contact members 7 and 8 as before, but such closure will 95 not take place until practically normal potential has momentarily returned to not only one but both of the temporarily segregated trolley or third-rail sections 51 and 53. Since it will be impossible to maintain full potential on any segregated trolley or third-rail section on which an abnormal ground 100 excessive overload or a short circuit occurs, it is evident that such a defective section will be kept isolated until such abnormality has been removed or corrected, when it will be promptly and automatically connected to the conducting network.

Those skilled in the art will understand that, although I have shown and described a circuit-breaker or interrupter of specific structure and connections, various modifications may be effected therein without exceeding the spirit and scope of my invention, and I desire that only such limitations shall be imposed as are indicated in the appended claims.

I claim as my invention:

1. In a circuit-controlling mechanism, the 125 combination with coöperating contact members, of electromagnetic means for effecting engagement of the contact members, and means normally connected magnetically in shunt with the said first means and depend- 130

ent upon the distribution of flux therein for causing the disengagement of the said contact members.

2. In a circuit controlling mechanism, the combination with coöperating contact members, and magnetic means for bringing said members into contact upon the occurrence of certain predetermined conditions on each of a plurality of circuit conductors, of magnetizable means linked with said first means and energized thereby for effecting the separation of said contact members.

3. In a circuit-closing mechanism, the combination with coöperating contact members, of electromagnetic means for effecting engagement of the said contact members upon the occurrence of predetermined conditions on each of a plurality of circuit conductors, and means normally associated in shunt with, and magnetically dependent upon, the distribution of flux in the said first means for causing the disengagement of the said contact members upon the occurrence of certain other predetermined conditions.

25 4. In a circuit interrupter, the combination with coöperating contact members, of electromagnetic means for bringing said members into contact upon the occurrence of certain predetermined voltage conditions on each of a plurality of conductors, and means magnetically associated with said electromagnetic means and energized thereby for causing the separation of said contacts upon the occurrence of certain other predetermined circuit conditions.

5. In a circuit interrupter, the combination with coöperating contact members, of electro-magnetically operated means dependent upon predetermined circuit conditions of a plurality of separate circuits for causing engagement of said coöperating members and means magnetically linked with said first means and dependent upon the distribution of flux therein for causing the separation of said coöperating members under predetermined abnormal conditions on any of said circuits.

6. In a circuit controlling mechanism, the combination with coöperating contact members, of electro-magnetic means responsive to predetermined electrical conditions of a plurality of separate circuits for causing the closure of said coöperating members, said means being adapted to maintain said closure while said predetermined conditions exist, and means magnetically associated with said closing means for causing said coöperating contact members to open.

7. In a circuit interrupter, the combination with coöperating contact members, of automatic electro-magnetic means for closing said coöperating contact members under predetermined voltage conditions on a plurality of separate conductors, and automatic means magnetically associated with said

closing means and energized thereby for opening said coöperating contact members under predetermined voltage conditions of any of said conductors.

8. In a circuit interrupter, the combination with coöperating contact members, of an electromagnet comprising a plurality of magnet coils each dependent upon the voltage condition of a separate conductor, common stationary and movable core members for said coils, said movable core member being adapted to cause engagement of said contact members only when all of said coils are energized a predetermined amount, and separate means dependent upon the distribution of the magnetic flux of said electromagnet for causing the separation of said contact members.

9. A circuit interrupter comprising a plurality of stationary contact terminals, a coöperating bridging contact member, two closing coils mounted co-axially, common stationary and movable core members for said coils, magnetizable members disposed between said coils, an armature normally maintained in engagement with said magnetizable members, a set of auxiliary contact terminals through which a common connection for said coils is completed when said armature is in its normal position, adjustable means for opposing the magnetic attraction normally exerted on said armature, and mechanical means for causing engagement of said auxiliary contact members when said interrupter is open.

10. In a circuit interrupter, the combination with coöperating contact members, and electro-magnetic operating means for one of said contact members comprising two exciting windings accumulatively connected and a single stationary and a single movable core member for said windings, said windings being connected to separate circuits and having a common return circuit, of magnetic means associated with said operating means and dependent upon the flux therein for deenergizing said exciting windings upon the occurrence of predetermined circuit conditions on either of said circuits.

11. In a circuit interrupter, the combination with coöperating stationary and movable contact members, and an operating magnet for said movable contact member comprising two magnet windings accumulatively connected and dependent for energization upon two separate circuits, and common stationary and movable core members for said magnet windings, said windings having a common return circuit, of electro-magnetic means for interrupting said common return circuit under predetermined conditions on either of said circuits, and means for automatically reestablishing said return circuit subsequent to the opening of said interrupter.

12. The combination with stationary and movable contact members, of operating means for said movable contact member comprising a single stationary and a single movable core member, exciting coils for said core members accumulatively connected to separate circuits, means for adjusting the initial air-gap between said core members, separated pole pieces of magnetic material disposed between said exciting coils, and a ring of highly conducting and non-magnetizable material located intermediate said first-named pole pieces, an armature adapted to be maintained in engagement with said magnetizable pole pieces under normal operating conditions, and means dependent upon the strength of the magnetic flux through said armature for causing the separation of the coöperating contact members. 50
13. In a circuit interrupter, the combination with coöperating contact members, and an electromagnet comprising a plurality of energizing coils for causing the engagement of said contact members, of means disposed between said coils and embodying a magnetic circuit in shunt to said electromagnet for effecting the separation of said contact members. 55
14. In a circuit interrupter, the combination with coöperating contact members and electromagnetic means for effecting the engagement thereof, of means embodying a normally closed magnetic circuit in shunt to said electromagnetic means for effecting the separation of said contact members. 60
15. In a circuit interrupter, the combination with coöperating contact members and an electromagnet comprising stationary and movable cores for effecting the engagement of said contact members, of means embodying a magnetic circuit in shunt around the gap between said cores for effecting the separation of said contact members. 65
16. In a circuit interrupter, the combination with coöperating contact members and an electromagnet comprising stationary and movable cores for effecting the engagement of said contact members, of means for normally deflecting a portion of the flux de- 70
- veloped in said cores, and means associated with said deflecting means for effecting the separation of said contact members when said deflected flux is weakened. 75
17. In a circuit interrupter, the combination with coöperating contact members and an electromagnet for effecting the engagement thereof, of magnetic means in shunt to said electromagnet and energized thereby for causing the separation of said contact members, and means for delaying changes in the flux shunted through said magnetic means. 80
18. An electromagnetic device comprising stationary and movable cores, an energizing winding therefor, an auxiliary magnetic path in shunt to said cores and means tending to prevent changes in flux traversing said auxiliary path. 85
19. In an electromagnetic device, the combination with stationary and movable cores, an energizing winding therefor, and a plurality of magnetizable members encircling said cores, of a conducting member also encircling said cores and disposed intermediate said magnetizable members, and a movable core member for normally engaging said magnetizable members, said conducting member encircling said cores being provided for preventing any rapid fluctuation of the flux in the said magnetizable members. 90
20. In a circuit interrupter, the combination with coöperating contact members, an electromagnet embodying two energizing coils having a common circuit, and a switching device in said circuit, of a plurality of stationary magnetic polar members disposed between said coils and a movable armature adapted to coöperate with said polar members for governing said switching device. 95
- In testimony whereof, I have hereunto subscribed my name this 29th day of November 1910.
